UNITED STATES PATENT OFFICE

107,640

DESIGN FOR AN ERASER HOLDING TIP FOR PENCILS

James De Quinzio, Jersey City, N. J., assignor to
Joseph Dixon Crucible Company, Jersey City,
N. J., a corporation of New Jersey

Application June 30, 1937, Serial No. 70,128

Term of patent 14 years

To all whom it may concern:

Be it known that I, James De Quinzio, a citizen of the United States and a resident of Jersey City, in the county of Hudson, in the State of New Jersey, have invented a new, original, and ornamental Design for an Eraser Holding Tip for Pencils, of which the following is a specification, reference being had to the accompanying drawings forming a part thereof and in which:—

Fig. 1 is a side elevation of an eraser holding tip for pencils embodying my new design, all the sides of the eraser holding tip being of substantially the same appearance as the side shown;

and Fig. 2 is a top plan of the eraser holding tip shown in Fig. 1.

The design is characterized by the ferrule having longitudinal alternate ribs and depressions, the depressions being relatively long and narrow, and the width thereof being greater than the width of the ribs, there being blank circumferential surfaces between the ends of the depressions and the bottom and top ends of the ferrule.

I claim: —

The ornamental design for an eraser holding tip for pencils as shown and described.

JAMES DE QUINZIO.
